UNITED STATES PATENT OFFICE.

HENRY SMITH BROWN, OF HARTFORD, CONNECTICUT.

SHRINKAGE-GAGE.

SPECIFICATION forming part of Letters Patent No. 271,411, dated January 30, 1883.

Application filed August 23, 1882. (No model.)

To all whom it may concern:

Be it known that I, HENRY SMITH BROWN, a citizen of the United States, residing in Hartford, in the county of Hartford and State 5 of Connecticut, have invented a new and useful Shrinkage-Gage, of which the following is a specification.

My invention is an instrument used in measuring the interior diameter of metal cylinders 10 and the exterior diameter of metal shafts, when such a cylinder is to be fastened around such a shaft by means of the natural contraction of the cylinder, due to its gradual cooling, or by means of the cylinder being forced 15 upon the shaft by hydraulic or other power. The cranks of stationary and of marine engines fastened to the shafts of such engines and the wheels of locomotives and railroad-cars fastened to their axles are instances of 20 such fastening of metal cylinders around metal shafts. It is well known that both these methods of fastening cylinders to shafts require that the diameter of the shaft be made somewhat larger than the interior diameter of 25 the cylinder; and experience has shown that the two diameters must be proportioned to each other with extraordinary accuracy, in order, on the one hand, to prevent the cylinder from breaking because of too great strain, 30 and, on the other hand, to prevent it from becoming loose because of too little contractile force. The difference between the diameter of the shaft and the interior diameter of the cylinder ought not to be less than one-tenth of 35 one per cent. nor more than two-tenths of one per cent. when the cylinder is to be fastened to the shaft by cooling after being expanded by heat; and where the cylinder is to be fastened to the shaft by pressure the difference 40 between the two diameters ought not to be less than three-fourths of one-tenth of one per cent. nor more than twice the latter amount.

It has heretofore been practicable by the use of calipers to make the diameter of a shaft 45 agree exactly with the length of a rod used to measure the interior diameter of the cylinder; but it has always been impossible to make the two measurements vary without sometimes varying more and sometimes varying less 50 than the particular case admitted or required. By the use of my invention that highly-useful

result can be accomplished with unvarying accuracy.

My invention is illustrated in the accompanying drawings, similar letters referring to 55 the same parts throughout the several views.

Figure 1 is a side view of my gage, as inserted in the cylinder the diameter of which is being measured by it. Fig. 2 is a central vertical section of Fig. 1. Fig. 3 is an edge 60 view of the gage after it is withdrawn from the cylinder and lengthened one-tenth of one per cent. by the insertion between two of its parts of the expansion-slip *g*. Fig. 4 is a specimen metal expansion-slip, preferably 65 made of steel, the smaller end of which is exactly nine one-thousandths of an inch thick, and therefore suitable for use when a nine-inch shaft is to be inserted in a corresponding cylinder. These slips are made to conform to the 70 exact thickness desired by the use of the well-known micrometer-calipers. The number desirable with each gage is the same as the number of different diameters of cylinders to be measured with that gage. Each slip may 75 be marked with figures showing its exact thickness, and also with other characters showing the diameter of the cylinder to which it is applicable. A sufficient variety of slips will enable the operator to expand the gage to the exact extent which the size of the cylinder, or the 80 nature of the metal, or the method of the fitting, or his own instructions or opinions relevant to amount of desirable shrinkage, or any or all of these considerations, may require in 85 each particular case.

a is a frame, one end of which is a tapering cylindrical split hub, threaded externally to receive the clamp-nut *b*, and threaded internally to receive the tube *c*. The tube *c* is 90 threaded internally to receive the adjustable spindle *d*. The check-nut *e* is also threaded to correspond with the thread of the spindle. The tube *c* is preferably closed at the bottom. The plug *f* forms a solid part of the frame *a*, 95 its purpose being to fill the hole, through which, in assembling the parts of the gage, the tube *c* is inserted into the frame. The tube may, however, be constructed with its lower portion small enough to pass through 100 the split hub, and in that case there need be no hole in the bottom of the frame, and there-

fore no plug to fill such a hole. In that event, however, the frame should receive a form at its lower end similar to the form of the lower end of plug *f*. The top of the plug, or if no plug is used then the corresponding part of the frame, should be ground into exact parallelism with the bottom of the tube *c*.

The operation is as follows: The clamp-nut and the check-nut are loosened and screwed back, allowing the bottom of the tube to be screwed firmly down upon the top of the plug, and allowing the spindle to be screwed up to such an extent as will cause the whole gage to exactly measure the diameter of the cylinder into which it is inserted. Thereupon the check-nut is screwed home, so as to lock the spindle against the top of the tube, and the gage is then taken away from the cylinder, and the tube is screwed up far enough to admit an expansion-slip of the requisite thickness between the bottom of the tube and the top of the plug; and after the expansion-slip is inserted the tube is screwed down hard upon it, and the clamp-nut is screwed home, so as to lock the tube with the frame. By these operations the gage is lengthened to an extent exactly equal to the thickness of the expansion-slip inserted, and its total length furnishes a perfect measure by which to turn the shaft for insertion into the cylinder. By means of

ordinary machinist's calipers the diameter of the shaft being turned may be made to correspond exactly with the length of the gage as expanded by the slip.

My shrinkage-gage may be variously modified without changing its essential character. A check-nut or a collar with a set-screw may be substituted for the clamp-nut *b*, and if the first-mentioned substitution is made the hub should not be split. So, also, a clamp-nut or a collar with a set-screw may be substituted for the check-nut *e*; but in case of either of those substitutions the tube *c* must be split at its upper end. These are examples of mechanical changes in my gage which will suggest themselves to those skilled in the art to which that instrument pertains.

I claim as my invention—

1. The combination, in a gage, of the frame *a*, the clamp-nut *b*, the tube *c*, the spindle *d*, the check-nut *e*, and the expansion-slip, substantially as described, or its equivalent.

2. The combination, in a gage, of the frame *a*, the clamp-nut *b*, the tube *c*, and the expansion-slip, substantially as described, or its equivalent.

HENRY SMITH BROWN.
